UNITED STATES PATENT OFFICE.

DAVID ALLEN, OF NEW YORK, N. Y.

CIGAR-VENDING MACHINE.

1,297,775.

Specification of Letters Patent. Patented Mar. 18, 1919.

Application filed December 13, 1916. Serial No. 136,731.

To all whom it may concern:

Be it known that I, DAVID ALLEN, a citizen of the United States, and resident of New York city, in the county of New York 5 and State of New York, have invented certain new and useful Improvements in Cigar-Vending Machines, of which the following is a specification.

My invention relates to vending machines 10 and has particular reference to a device of the class described adapted particularly for vending cigars.

The primary object of my invention is to provide a device of the class described which 15 after being emptied will not receive a coin or permit the same being deposited in the coin receptacle.

Another object of my invention is to provide means associated therewith to prevent 20 the bridging of the cigars over the delivery drum.

A still further object of my invention is to provide a moistening means associated therewith to prevent the cigars from becoming 25 extremely dry, which is an objection against the cigar vending machines now in common use.

A still further object of my invention resides in the provision of a device of the character described that is simple in construction, efficient in operation and that can be manufactured and placed on the market at a minimum cost.

Other objects as well as the nature, character 35 of my invention will be more readily understood from the following description taken in connection with the accompanying drawings and pointed out in the claims forming a part of 40 this specification, in which—

Figure 1 is a front elevation of the outer casing of my invention;

Fig. 2 is a top plan view of the same with the sliding cover removed;

Fig. 3 is a vertical sectional view of my 45 invention showing a cigar about to be delivered;

Fig. 4 is a top plan view of a humidor used in connection with my invention;

Fig. 5 is a top plan view of the means 50 employed in my invention to insure the uniform delivery of the cigars to the discharge drum, and

Fig. 6 is a perspective view of the dis-

charge and the means for retaining the same 55 to prevent rotation thereof when the casing has been emptied of the cigars.

Referring more particularly to the drawings wherein similar characters of reference designate like and corresponding parts 60 throughout the various views, A designates my invention in its entirety having a base 1, and end walls 2 and 3, the lower edge of the wall 3 being provided with an opening 4 to permit the discharge of the cigars. Side 65 walls 5 and 6 are mounted on the said casing and provided with longitudinal grooves therein to permit the top 7 to be slidably mounted thereon. The end wall 2 is hingedly connected by means of hinges 8 mounted on 70 one edge thereof and provides means for gaining access to the humidor and also for removing the top. A discharge drum 9 is rotatably mounted in the side walls and is provided with a longitudinal recess 10. A 75 spring 12 is mounted within the said recess to normally retain the cigar in alignment with the periphery of the drum 10. A pair of corrugated rubber strips 13 are mounted transversely of the roller to provide means 80 for preventing the bridging of the cigars and are used in conjunction with a small screw having an enlarged head 13' which is mounted adjacent the said longitudinal slot over the periphery of the drum, the said screw being adapted to engage a supporting plate 14 and thus agitate the same upon the rotation of the drum. The plate 14 is suspended or detachably mounted on a pair of lugs 15 and 16 mounted on the side walls. 85 The said plate 14 comprises a sheet of metal having the edges thereof bent laterally of the body portion. One of the said bent portions providing means for retaining the said plate in the desired position and the opposite end 90 providing guiding means for the cigar upon the rotation of the said drum. A transverse strip 17 forming a brace means for the end of the casing of my device when the door thereof is in open position is provided with a supplemental plate 18 having a cushioning means 19 provided on the under side thereof to engage the supporting plate 14 to hold the latter in position and at the same time prevent the cigars dropping or 95 being retained between the plate 14 and the transverse strip 17. A winged spring 18a is secured to the strip 17 and when the door

is secured to the strip 17 and when the door

2 is closed, said spring is disposed into engagement with the depending portion of the plate 14 to hold the plate 14 inwardly displaced, but to permit opposite movement thereof when engaged by the head 13', so as to permit the latter to pass the inner depending portion of the plate 14, when the drum is turned to dispense the cigars.

On the opposite side of my rotating roller 10 are provided a pair of strips 20' rigidly connected to the side walls of the casing, the said strips being mounted on a slant for a purpose which will hereinafter appear. A plate 20 is detachably mounted on the said 15 strips and having the edges thereof bent similar to those described to the supporting plate 14 and for the same reasons.

The supplemental plate is detachably engaged with the end wall 3 of my invention 20 by means of a screw or other securing means 21 fastened to the said wall and engaging the body portion of the said plate. A lateral extension 22 is provided on the said body portion extending over the supporting 25 plate 20 to retain the same in the desired position and also providing means for aligning the cigars so that they will be fed to the rotating drum in the desired position. A cushioning means 23 is mounted on the 30 under side of the said supplemental plate to prevent scratching of the plate 20, in the same manner that the cushion 19 coacts with the plate 14, as well as to firmly hold the plates in position.

35 The locking means for my invention comprises a sheet metal plate 24 rigidly secured to the side walls of my invention and provided with a plurality of transverse openings 25 for a purpose which will hereinafter 40 be described. A lateral extension 26 is provided on the free end of the sheet metal plate 24 to prevent the cigars from being deposited before reaching the desired position. An opening is provided intermediate the ends 45 of the said laterally bent portion 26 to permit a catch 27 which is hingedly connected to a cleat 28 to engage the roller 9. The free end of the cleat 28 is provided with an opening therein to receive a bolt 29 which 50 detachably secures the said cleat in a central transverse opening and also retains a spring 30 in engagement with the catch 27 to engage the same with the drum 9. The end of the catch 27 is flared as at 31 to permit the 55 said drum being freely rotated. A plate 32 is adjustably secured to the transverse slots 25 having a diverging or downturned end portion to deflect cigars when discharged from the roller or drum 9. A plurality of parallel slanting cleats 33 and 34 are mounted in spaced relation to the side walls to permit the humidor supporting plate 35 to slide between the said cleats, the free end of the said plate having a trans- 60 verse strip 36 mounted thereon to limit the 65

movement of the plate. A strip of sheet metal 37 having the ends thereof bent in opposite directions provides a retaining means for the humidor and also a supporting means for a foraminous plate 38 which is secured to one of the said bent edges. A receptacle 39 is mounted on the said plate and retained therein by means of a pair of wings 40 formed on the strip 37. A standard 41 is mounted on the base 1 to provide a supporting means for a plate 42 having one end thereof secured to the standard and the opposite end engaging the base plate adjacent the opening 4 provided in the end wall 3 of the casing. An extension 43 is provided on one end of my casing to provide a supporting means for a well consisting of a sheet metal plate having a body 44 secured to the said extension and having the opposite ends thereof bent to form diverging end portions 45 and 46. A plate 47 is secured to the end wall 3 above the opening 4 and provided with a diverging wing portion 48 to deflect the water away from the said opening. A strip of spring metal 49 is secured to the base and having the free end thereof engaging the standard 41. The strip 49 thus provides a coin chute to distribute the same if the section designated R which forms a coin retainer thus preventing the same from closing the outlet of the coin receiving receptacle 50 and a consequential locking of the machine against operation. A designating plate 53 is mounted on the side wall adjacent the coin receptacle to provide means for retaining a transparent plate and card to indicate the grade of cigar in the machine and also the price thereof.

The operation of my invention is as follows: Upon the insertion of a coin in the coin receptacle 50 the handle 51 is rotated and if a cigar is in the longitudinal groove of the rotatable drum the same will be permitted to rotate beyond the shelf 32 after the coin has dropped into the coin retainer R and the cigar deposited on the plate or chute 42, from where it slides into the well 44. If on the other hand the cigars have been previously exhausted the catch 27 will engage the longitudinal opening as shown in Fig. 6 and prevent further movement of the roller. Thus the spring 52 will cause the return of the roller to its original position when the coin will be returned to the person operating the same. It is of course obvious that when the cigar is in the groove, irrespective of its size the spring 12 will force the same into engagement with the catch 27 thus preventing the said catch from engaging with the groove.

The desired method of refilling my case with cigars is to insert a box of cigars through the door 2 in an inverted position depositing them as desired upon the removal of the top.

From the above description taken in connection with the accompanying drawings, it can easily be seen that I have provided a device that is simple in construction, containing but few simple parts that can be cheaply manufactured and assembled and when assembled can be placed upon the market and sold at a minimum cost.

It will be understood that the above description and accompanying drawings comprehend only the general embodiment of my invention and that various minor changes in detail of construction, proportion and arrangement of parts may be made within the scope of the appended claims and without sacrificing any of the advantages of my invention.

Having thus fully described my invention, what I claim as new and desire to secure by Letters Patent, is:—

1. In a cigar vending machine, the combination with a casing having side and end walls, of a hopper-shaped receptacle formed therein and comprising a plurality of slanting plates detachably mounted in the casing, a drum rotatably mounted in the said casing, means for resiliently holding one of said plates toward said drum, the said drum having a longitudinally extending groove therein to receive a cigar, a spring member mounted in said groove, and means mounted in the casing to prevent rotation of the drum when the cigars have been exhausted.

2. In a cigar vending machine, a casing having side and end walls, a plurality of supporting lugs mounted on the side walls of the casing, a pair of slanting plates detachably associated with the said lugs, one end of the said plates being bent laterally thereof to limit the movement of the plates and retain the same in the desired position, the opposite ends of the plates being bent to form guiding means, a drum rotatably mounted in the side walls of the casing, means carried by said drum for engaging the plates to agitate the same when the drum is rotated, means for rotating the drum, the said drum having a longitudinally extending groove to receive a cigar, a spring member provided in the said groove to force the cigar into a position alining with the periphery of the drum, a supporting shelf member rigidly connected to one of the side walls of the casing and having a plurality of transverse slots, a cleat adjustably mounted in the said slots, a catch hingedly connected to the said cleat, a spring mounted on the said cleat, the free end of the spring being in engagement with the catch for a purpose specified.

3. In a vending machine of the class described, a casing having side and end walls, a door pivotally connected to one side wall forming a closure for one end thereof, a top slidably mounted on the casing side and end

walls, a plurality of supporting lugs mounted on the side walls of the casing, a pair of slanting plates detachably associated with said lugs, one end of each of said plates being bent downwardly to limit the movement of the plate and retain the same in position, the opposite ends of the plates being bent to form guiding means, a drum rotatably mounted in the side walls of the casing, said drum having a longitudinally extending groove to receive a cigar or the like, spring means holding certain of said plates toward said drum, means carried by said drum to engage said plates during the rotation of the drum to force said plates in a reverse position, means for forcing the cigar in the groove to a position alining with the outer periphery of the drum, a supporting shelf member rigidly connected to one of the walls of the casing and having an upright inner end, said upright end being disposed adjacent to the periphery of the drum, a down turned member at the inner end of said shelf member, and means supported upon said shelf member and operating through said upright end to normally engage the drum, but permit the rotation thereof and passage of the cigars or other articles carried within the groove thereof, said means being adapted to engage said groove to prevent rotation of the drum, when the supply of cigars or the like is exhausted.

4. In a vending machine of the class described, a casing having side and end walls, a door pivotally connected to one side wall forming a closure for one end thereof, a top slidably mounted on the casing side and end walls, a plurality of supporting lugs mounted on the side walls of the casing, a pair of slanting plates detachably associated with said lugs, one end of each of said plates being bent downwardly to limit movement of the plate and retain the same in position, the opposite ends of the plates being bent to form guiding means, a drum rotatably mounted in the side walls of the casing, said drum having a longitudinally extending groove to receive the cigar or the like, spring means holding certain of said plates during the rotation of the drum, means carried by said drum to engage said plates during the rotation of the drum to force said plates in a reverse position, means for forcing the cigar in the groove to a position alining with the outer periphery of the drum, a plurality of transverse slots therein, a shelf, a cleat adjustably mounted on said shelf, a catch hingedly connected to the said cleat, a spring mounted on the said cleat, the free end of the spring being in engagement with the catch, said casing having a transverse opening adjacent the lower edge of the side wall thereof, an inclined chute forming plate disposed to receive the cigars from the drum,

and a well mounted on an extension of the casing adjacent to said opening, to receive the cigars as discharged.

5. In a vending machine of the class described, a casing having side and end walls, a door pivotally connected to one side wall forming a closure for one end thereof, a top slidably mounted on the casing side and end walls, a plurality of supporting lugs mounted on the side walls of the casing, a pair of slanting plates detachably associated with said lugs, one end of each of said plates being bent downwardly to limit movement of the plate and retain the same in position, the opposite ends of the plates being bent to form guiding means, a drum rotatably mounted in the side walls of the casing, said drum having a longitudinally extending groove to receive the cigar or the like, spring means holding certain of said plates during the rotation of the drum, means carried by said drum to engage said plates during the rotation of the drum to force said plates in a reverse position, means for forcing the cigar in the groove to a position alining with the outer periphery of the drum, a plurality of transverse slots therein, a cleat adjustably mounted on said shelf, a catch hingedly connected to the said cleat, a spring mounted on the said cleat, the free end of the spring being in engagement with the catch, the base of said casing extending beyond the end wall, a well mounted on the extension to receive the cigars as dispensed, a standard formed on the said base, a trough member having one end rigidly connected to the said standard and the opposite end thereof being flexed into engagement with the base adjacent the said opening, as and for the purposes specified.

6. In a vending machine of the character described, a casing having side and end walls, a top and a bottom wall, a discharge opening being provided in one end wall, a well disposed adjacent to said opening at the bottom thereof, means for obtaining access to the casing, a hopper in said casing, said hopper comprising inclined plates, one of

said plates being slidable and adapted to be agitated, a drum rotatable in the casing and having a receiving groove, means for rotating the drum, and means for agitating the plate.

7. In a vending machine of the character described, a casing having side and end walls, a top and bottom wall, a discharge opening being provided in one end wall, a well disposed adjacent to said opening at the bottom thereof, means for obtaining access to the casing, a hopper in said casing, said hopper comprising inclined plates, one of said plates being slidable and adapted to be agitated, a drum rotatable in the casing and having a receiving groove, means for rotating the drum, means for engaging said drum to limit the rotation thereof upon the supply of cigars or the like being exhausted, means for holding said slidable plate toward the drum, means carried by the drum for displacing said plate and agitating the same, upon the drum being rotated to receive and discharge a cigar or the like, and means carried by the drum for arranging the articles to be vended thereon.

8. In a vending machine of the character described, a casing having side and end walls, a top and bottom wall, a discharge opening being provided in one end wall, a well disposed adjacent to said opening at the bottom thereof, means for obtaining access to the casing, a hopper in said casing, said hopper comprising inclined plates, one of said plates being slidable and adapted to be agitated, a drum rotatable in the casing and having a receiving groove, means for rotating the drum, means for engaging said drum to limit the rotation thereof upon the supply of cigars or the like being exhausted, means for holding said slidable plate toward the drum, and means carried by the drum for displacing said plate and agitating the same, upon the drum being rotated to receive and discharge a cigar or the like.

In testimony whereof, I affix my signature hereto:

DAVID ALLEN.
